UNITED STATES PATENT OFFICE.

WILLIAM E. DEAN, OF SUPERIOR, WISCONSIN.

TUNNELING-MACHINE.

1,156,277.

Specification of Letters Patent. Patented Oct. 12, 1915.

Application filed September 12, 1912. Serial No. 720,077.

To all whom it may concern:

Be it known that I, WILLIAM E. DEAN, a citizen of the United States, residing at Superior, in the county of Douglas and State of Wisconsin, have invented certain new and useful Improvements in Tunneling-Machines, of which the following is a specification, reference being had therein to the accompanying drawing.

10 My invention relates to improvements in tunneling machines.

This invention consists of certain new and useful improvements in tunneling machines and relates particularly to such a machine 15 for tunneling rock or such like substance.

The object is to provide a machine of the class named, in which the extent of cut upon the face of the work engaged is at all times predetermined, that is to say, the reciprocating drills do not work at right-angles to the face of the rock, but being carried at an angle to the radial line of their vertical movement establish a new working plane at each advancement into the face of the work 20 engaged—thus taking a depth of slice predetermined at each upward movement of the drill battery, the battery being advanced each time when the drills are in their lowermost position until the entire face of the cutting bit engages the face of the surface being cut, then when raised on the arc of a circle whose radial line is at a fixed angle to the center line of the drills, maintain the depth of cut first established up the entire 25 face of the work.

Another object of my invention is to provide a tunneling machine of this character which is simple in construction and effective in operation and having certain details of 40 structure hereinafter more fully set forth.

In accompanying drawings, Figure 1 is a vertical longitudinal section of the end of a tunnel showing a side elevation of my improved tunneling machine; and Fig. 2 is a 45 horizontal longitudinal section.

A strong rigid supporting frame is formed of preferably fabricated metal construction, comprising the base, 1; vertical columns 2—2 and top 3, this frame being carried 50 upon two suitably constructed skids or runners, 4 which are designed to be movable longitudinally upon the floor of the tunnel.

Within the columns 2 and at the four corners of the supporting frame are carried 55 rods or shafts, 5—5 and 6—6, the frame ends of the same being screw threaded and

susceptible of longitudinal movement independent of the frame but supported thereby, and for such longitudinal movement I prefer to employ internally screw threaded 60 chain driven, sheaves or sprockets, 7, which may be operated in any desired manner for the purpose, or the shafts 5—5 and 6—6 may be reciprocated in any other manner without departing from the spirit of my invention. 65

The forward ends of the shafts 5—5 are pivotally supported by skids 8 and designed to move back and forth upon the floor of the tunnel. The forward ends of the shaft 6—6 are each pivotally supported by a shoe 9 engaging the roof 3 of the supporting frame and which are formed integral with a downwardly extending segmental shaped, toothed rack 10, which racks are each pivotally mounted upon the shoes 8 as illustrated in 70 Fig. 1 at 11. Thus the racks 10—10 are susceptible of fore and aft movement independent of the supporting frame.

The racks 10—10 are gear toothed on both sides their entire length and are each engaged by twin gears 12, designed to be operated preferably by worm gears 13 from suitable power such as a motor 14 or in any manner whereby the gears 12, may be slowly and forcibly operated in either direction for 85 raising and lowering the battery of drills controlled thereby.

15 represents the reciprocating drills either air, electricity or steam operated, the two outside pairs of which are rigidly fixed 90 to the gear casing 16 of the gears 12 and are carried thereby, the intermediate drills between the two pairs above mentioned are designed to be rigidly fixed to the side pairs by through bolts 17 so that the entire battery of drills are at all times in the same 95 plane and operate vertically in unison.

The drills 15 are fixed to the gear casing 16 at an angle differing from that of the radial line of the racks 10—10 and gears 12, 100 so that the face of the cutting bits are not in a plane parallel with the arc of the rack, they being at all times advanced slightly to the plane of the preceding cut as clearly shown at 18, Fig. 1, of the drawings.

105 It is understood that the battery of drills are designed to operate against the face of the tunnel, from the bottom upward, thus when a cut is to be made, the drills are placed in the position shown in the drawings and gradually advanced while at work until, the entire face of the bits are engaged, 110

when the forward motion is stopped and the battery gradually raised up the face of the tunnel, the depth of cut being fixed by the angle of the face of the bits. Thus it is evident the entire face of the bit will impinge the surface being cut as the battery is raised, whereas, if the drills were carried in line with the radius of the racks as is common, only the upper edge of the bits would be engaged in work by which arrangement great strain upon the drills and entire mechanism is avoided and much better and easier work accomplished.

I prefer to have the cutting bits of the drill sufficiently large to cover collectively the entire surface laterally of the face to be worked and to operate the reciprocation of the drills consecutively.

Having thus described my invention what I claim is:

1. A tunneling machine, comprising a vertically disposed support, horizontally adjustable arms carried by the support, shoes carried by the outer ends of the support, segmental rack bars pivotally connecting the shoes, a drill support surrounding the rack bars, a battery of drills carried by the support, pinions carried by the drill support and meshing with the rack bars, and means for rotating said pinion whereby the battery of drills may be moved in an arc of a circle.

2. A drilling machine comprising a vertically disposed support, horizontally arranged adjustable arms carried by the upper and lower ends of said support, shoes pivotally carried by the outer ends of the said arms, segmental racks connecting the upper and lower shoes, a drill support surrounding the rack bars, a battery of drills carried by the support, pinions carried by the drill support and meshing with the rack bars, means for rotating said pinions whereby the battery of drills may be moved in an arc of a circle.

3. A drilling machine, comprising a vertically disposed frame, horizontally arranged rods extending through the said frame at its upper and lower ends, and screw threaded sprockets on said rods within the frame, means for operating said sprockets whereby the rods are longitudinally adjustable, shoes carried by the outer ends of the rods, segmental rack bars connecting the upper and lower shoes, a drill support surrounding the rack bars, a battery of drills carried by the support, pinions carried by the support and meshing with the rack bars, and a worm driving said pinions whereby the battery of drills may be moved vertically in an arc of a circle.

4. A drilling machine, comprising a vertically disposed frame, horizontally arranged rods extending through the frame at its upper and lower ends and threaded, sprockets on said threaded rods within the

frame, means for moving the said sprockets in unison, shoes pivoted and carried by the outer ends of the rods, rack bars rigidly carried by the upper shoe and having its lower end pivotally connected to the lower shoe, a drill support surrounding the rack bars, a battery of drills carried by the support, pinions carried by the support and meshing with the rack bars, and a worm driving said pinions, whereby the battery of drills may be moved vertically in an arc of a circle.

5. A drilling machine comprising a vertically disposed frame, horizontally arranged rods extending through the frame at its upper and lower ends and threaded, sprockets on said threaded rods within the frame, means for moving the said sprockets in unison, shoes carried by the outer ends of the rods, rack bars rigidly carried by the upper shoe and having its lower end pivotally connected to the lower shoe, a drill support surrounding the rack bars, a battery of drills carried by the support, pinions carried by the support and meshing with the rack bars, a worm for driving said pinions, and means for driving said worm substantially as shown and described.

6. A drilling machine comprising a frame, a skid for supporting said frame, horizontally arranged rods carried by the upper and lower ends of the frame, screw threaded sprockets on said rods within the frame, means for operating said sprockets in unison whereby the rods are simultaneously adjusted in either direction, a plate carried by the upper end of said frame, shoes carried by the outer ends of the upper rods and resting against the plate, shoes pivotally carried by the lower rods, segmental rack bars rigidly carried by the upper shoes, and pivotally connected to the lower shoes, a drill support surrounding the segmental rack bars, a battery of drills carried by the support, pinions carried by the support and meshing with the segmental rack bars, a worm operating said pinions and means operating the said rack, substantially as shown and described.

7. A tunneling machine, comprising a vertically disposed support, horizontally adjustable arms carried by the support, segmental rack bars carried by the arms, a drill support surrounding the rack bars, a battery of drills carried by the support at an angle to the radial line of the support, pinions carried by the drill support and meshing with the rack bars, and means for rotating said pinions.

8. A drilling machine, comprising a vertically disposed support, horizontally arranged adjustable arms carried by the upper and lower ends of said support, shoes pivotally carried by the outer ends of said arms, segmental racks connecting the upper and lower shoes, a drill support surround-

ing the racks, a battery of drills carried by the support at an angle to the radial line of the support, pinions carried by the drills and meshing with the rack bars, and means for rotating said pinions whereby the battery of drills may be moved in an arc of a circle, substantially as shown and described.

In testimony whereof I hereunto affix my signature in the presence of two witnesses.

WILLIAM E. DEAN.
